COIN TRICK APPARATUS

Frank Renz, Philadelphia, Pa.

Application October 17, 1947, Serial No. 780,511

3 Claims. (Cl. 272—8)

1

My invention relates to apparatus for performing coin tricks, and more particularly to apparatus wherein a coin is apparently caused to disappear and reappear as a stack of coins.

With the foregoing in view, an object of my invention is to provide improved apparatus for performing coin tricks.

A further object is to provide improved apparatus for performing coin tricks which includes a cylindrical shell having its periphery formed to simulate a stack of coins.

A further object is to provide an improved apparatus for performing coin tricks such as that last described which includes a hollow, cup-shaped case adapted to receive said shell therein with a coin interposed between the top of said shell and the bottom of said case, together with means for retaining said shell, coin and case in assembled relation.

A further object is to provide an improved coin-trick apparatus such as that last described which includes means for readily separating said assembled shell, coin and case.

Other objects and advantages reside in the particular construction of the invention, combination and arrangement of the several parts thereof, and will be readily understood by those skilled in the art upon reference to the attached drawings in connection with the following specification, wherein the invention is shown, described and claimed.

In the drawings:

Figure 1 is a perspective view showing an element of the invention inverted;

Figure 2 is a like view of a second element of the invention inverted;

Figure 3 is a perspective view of a third element of the invention;

Figure 4 is a transverse vertical section showing the elements of Figures 1, 2 and 3 in assembled form;

Figure 5 is an enlarged fragmentary elevation of the element of Figure 1;

Figure 6 is a perspective view of the element of Figure 1 showing a coin applied thereto.

In the drawings, wherein like reference characters have been used to designate like parts, and referring more particularly to Figures 3 and 4, 10 designates a cylindrical ring having an upper free edge 11 and a lower free edge 12.

Referring now to Figure 2, a cup-shaped case or shell 13 comprises a cylindrical side wall 14, a free lower edge 15, a closed top 16, and a radially outwardly-directed top flange 17 extending from the top outwardly of the side wall 14.

2

The length of the side wall 14 below the flange 17 of the case or shell 13 is substantially shorter than the length of the side wall of the ring 10. Moreover, the outer diameter of the side wall 14 of the case 13 is slightly less than the internal diameter of the ring 10, whereby the case 13 is adapted to be telescoped within the ring 10 and supported on the upper edge 11 thereof by the under side of the flange 17. As is clearly shown in Figure 4, in this position the lower free edge 15 of the case 13 is vertically spaced from the lower edge 12 of the ring.

Referring now to Figures 1, 5 and 6, 20 designates generally a cylindrical body which may 15 comprise an inverted cup-shaped, hollow shell having a cylindrical side wall 23, a free lower edge 22, and a closed top 25. The outer periphery of the side wall 23 is grooved, as at 24, and the upper closed edge of the side wall is beveled, as 20 at 27, whereby in elevation the shell 20 simulates a stack of coins. The outer periphery of the free lower edge is outwardly flared slightly, as at 26, for a purpose to be described later. Thus, when a coin 28 of a denomination equivalent to 25 that simulated by the grooves and beveled edges 24 and 27 of the shell 20 is seated atop the top 25 of the shell, the arrangement simulates a stack of coins, which simulation is made to appear more genuine by the appearance of the coin 28 atop the stack.

Obviously, the shell 20 may be used alone or in conjunction with a coin 28 to create the illusion of a stack of coins, but it is preferable to utilize it in connection with a coin-disappearing 35 illusion, wherein the empty shell or case 13 is supplied with a coin 28 against the top 16 thereof inwardly of the cylindrical wall 14. The illusionist now surreptitiously inserts the shell 20 into the case 13, whereby the coin 28 is interposed between the tops 25 and 16 of the case and shell. Display of the interior of the shell 20 now creates the illusion that the coin 28 has 40 vanished. This illusion is heightened by the fact that the flange 17 of the case extends below the inner surface of the top 16, whereby to create the illusion that the case has a relatively 45 thick top. The assembled shell, case and coin may now be inserted in the ring 10 in the Figure 4 position, and the top 16 of the case may be 50 tapped, or the assembly may be tapped on a desk or table, whereby the shell 20 and coin 28 are dropped from the case 13 to create the illusion of a stack of coins having been mysteriously created out of thin air. The shell 20 and case 13 are retained in assembled relation by 55

means of the outwardly-directed flange or flaring 26 on the lower free edge 22 of the shell. This flange 26 is of very slight nature, so that it is not readily discerned by the eyes of the beholders, but, nevertheless, is sufficiently great to cause a frictional engagement with the inner periphery of the case 13 as the parts are assembled. Thus, the assembly is retained together frictionally, but is readily separated by a slight tap as aforesaid. In this connection, it should be noted that the lengths of the side walls 14 and 23 of the case and shell are such that the free edges 15 and 22 thereof lie flush with each other when a coin is interposed between the two bottoms and the members are nested together.

While I have shown and described what is now thought to be the preferred embodiment of my invention, it is to be understood that the same is susceptible of other forms and expressions. Consequently, I do not limit myself to the precise structure shown and described except as hereinafter claimed.

I claim:

1. Apparatus for performing a coin trick, comprising a cylindrical ring having free upper and lower edges, an inverted cup-shaped case having a cylindrical side wall having a free lower edge, a closed top and a radially outwardly-directed flange, said case being adapted to be suspended concentrically within said ring with said flange seated atop said upper edge of the same and with said free edge of said wall above said lower edge of said ring, an inverted cup-shaped shell having a closed top and a cylindrical side wall having a free lower edge, the internal diameter of said case being substantially equal to that of a coin of given denomination and to the outside diameter of said shell, the outer periphery of said side wall of said shell being formed to simulate a stack of coins of said denomination, said case being adapted to receive a coin of said denomination and said shell therein concentrically thereof with said top wall of said shell holding said coin flatly against said top wall of said case, said free edge of said side wall of said shell being radially outwardly-flared to grip the inner periphery of the lower edge of said case and frictionally retain said shell therein.

2. Apparatus for performing a coin trick com-

prising a cylindrical ring, a shell having one end closed and having the other end open, said shell being provided with an external flange adjacent the closed end, the shell being arranged so that its open end extends into said ring with said flange seated on the adjacent end of said ring, a second shell having one end closed and having the other end open, said second shell being of a diameter less than the diameter of said first named shell, the second named shell being arranged so that its closed end is positioned within said first named shell and spaced from the closed end of the first named shell to thereby provide a space for the interposition therein of the coin of a given denomination, the outer surface of said second named shell being formed to simulate a stack of coins of said denomination.

3. Apparatus for performing a coin trick comprising a cylindrical ring, a shell having one end closed and having the other end open, said shell being provided with an external flange adjacent the closed end, the shell being arranged so that its open end extends into said ring with said flange seated on the adjacent end of said ring, a second shell having one end closed and having the other end open, said second shell being of a diameter less than the diameter of said first named shell, the second named shell being arranged so that its closed end is positioned within said first named shell and spaced from the closed end of the first named shell to thereby provide a space for the interposition therein of the coin of a given denomination, the outer surface of the said second named shell being formed to simulate a stack of coins of said denomination with the second named shell along its open end being flared outwardly to grip the adjacent inner surface of the first named shell and frictionally retain the second named shell in the first named shell.
